UNITED STATES PATENT OFFICE.

JOHN A. KROPP, OF NEWARK, NEW JERSEY, ASSIGNOR, BY MESNE ASSIGNMENTS, TO
WESTERN ELECTRIC COMPANY, INCORPORATED, A CORPORATION OF NEW YORK.

SUBSTATION-SENDER.

1,200,856.

Specification of Letters Patent. Patented Oct. 10, 1916.

Application filed September 26, 1914. Serial No. 863,633.

To all whom it may concern:

Be it known that I, JOHN A. KROPP, a citizen of the United States of America, residing at Newark, in the county of Essex 5 and State of New Jersey, have invented a new and useful Improvement in Substation-Senders, of which the following is a full, clear, concise, and exact description.

This invention relates to improvements in 10 impulse-sending devices of the kind used in transmitting current impulses for the operation of selective circuit-controlling devices which may be located at a central office for the purpose of extending a connection 15 through from one party to another or they may be located at separated stations upon the same line and adapted to close a signaling circuit.

The object of this invention is to provide 20 a sender where the manipulations on the part of the operator are especially simple, and consist merely in the moving of a handle around a number dial, from whatever position it might have, to the number 25 wanted followed by the depression of a projection on the handle into a hole adjacent to the figure.

In this invention there is provided a power storing mechanism which may be operated by the rotation of the handle in either 30 direction, and is adapted during the first few manipulations thereof to store up a sufficient supply of power to last during several successive manipulations, thereby eliminating the necessity of operating this part of 35 the mechanism every time a subscriber's number is selected. An automatic controlling device is therefore provided for the release of this part of the mechanism, from 40 control by the operator of the handle, whenever a full supply of power has been stored. There is further provided a means for controlling the number of impulses to be sent by 45 each selective manipulation, and a mechanism associated therewith for locking the handle in operated position until such impulses have been sent. This arrangement makes it possible to select and send the digits in rapid succession without confusion. 50 and with the most economical use of power.

The several features of my invention may be more readily understood by reference to the accompanying drawings in which—

Figure 1 is a perspective view with parts

broken away of a mechanism embodying this 55 invention; Fig. 2 is a perspective view showing certain details of the mechanism; Fig. 3 is a fragmentary perspective view of other details of the mechanism; Fig. 4 is a front view of the mechanism with parts broken 60 away; Fig. 5 is a cross-sectional view taken on the line 5—5 of Fig. 4; Fig. 6 is a sectional view taken on the line 6—6 of Fig. 5; Fig. 7 is a cross-sectional view of the power 65 storing mechanism showing the driving clutch in operative position; Fig. 8 is a fragmentary view showing details of the mechanism.

The same letters of reference are used to 70 designate the same parts wherever shown in the drawings.

The mechanism which is employed for the storing of power to be used in the sending of impulses is operated by the turning of the handle 10 in either direction during the selection of a subscriber's number, and sufficient power may be stored up by only a few movements of the handle to last for the selection of several numbers. This mechanism consists of a shaft 11 running longitudinally 80 through the center of the machine, which is adapted to operate a claw clutch consisting of two members 12, 13, each of which has projections which fit into recesses of the other. The driving member 12 is slidably 85 mounted and keyed to shaft 11, by means of the longitudinal slots 14 therein being engaged by a pin 15 on the shaft, so that it may readily be disengaged from its mate, the driven member 13, which is mounted 90 loosely on the shaft 11. This member 13 is attached to a disk 16 which forms the support for two spring-pressed pawls 17, 18 located on opposite sides thereof. Located on the upper side of the disk 16 is the 95 ratchet wheel 19 adapted to be engaged and rotated by the pawl 17 when the disk is turned in a clockwise direction, and located on the opposite or under side of disk 16 is a similar ratchet wheel 20 adapted to be engaged and rotated by the pawl 18 when the disk is turned in a contraclockwise direction. 100

The spiral spring 21 has its inner end attached to the operating sleeve 22 surrounding the shaft 11, and its outer end attached 105 by means of a loop to a pin 23 on gear wheel 24. This spiral spring is adapted to be wound in clockwise direction, and through

the medium of the claw clutch and pawl and ratchet mechanism just described. This is done directly by the pawl 17 engaging ratchet wheel 19 which is attached, by means of four posts 25, to the gear wheel 24, and indirectly by the pawl 18 engaging the ratchet wheel 20, which is coupled by means of a train of gears to the gear wheel 24. Said train of gears consists of gear wheels 26, 27, 28 and 29, gear 26 being attached to ratchet wheel 20, gear 27 being mounted between a bracket 30 and the bottom plate 31, and gears 28 and 29 being fixed on shaft 32 which is mounted between a bracket 33 and bottom plate 31. This arrangement will give to the gear wheel 24 the same direction of rotation regardless of which of the two ratchet wheels 19 and 20 may be actuated by the shaft 11. The direction of rotation of all these parts is marked by means of arrow points in Fig. 1. It may be mentioned here that the operating sleeve 22 is the medium through which the energy stored up in the spring is transmitted to a mechanism for the sending of impulses, which will be fully set forth as the description proceeds.

There is provided an automatic controlling device for the claw clutch by means of which a continuous supply of power is maintained in the spring during selecting operations. The driving member of said clutch, for that purpose, first, is caused to automatically engage with its mate and allowed to wind the spring until the proper amount of power has been stored up in the same, and, second, is caused to be automatically disengaged until such a time as the stored up power in the spring has been exhausted. These automatic actions of the driving clutch member take place alternately and are controlled by a feed screw 34 slidably mounted on a carrier hub 36 and having the pins 37, passing through the longitudinal slots 38 cut in the hub and engaging a groove in the periphery of the driving clutch member 12. By this arrangement, this clutch member 12 is made to participate in the longitudinal movement of the feed screw, but not in a rotary movement of the same that may take place at intervals and the purpose of which will hereinafter be made clear. The carrier hub 36 as well as the feed screw 34 will participate in rotary movements of the operating sleeve 22 on account of the hub 36 being attached permanently to the sleeve 22 by means of two screws 39. A guide nut 40 is adapted to engage the thread on the feed screw 34 for the purpose of guiding and controlling the movement of said screw. Said nut is held in a fixed angular relation to the ratchet wheel 19 and gear wheel 24 by means of two ears 41 on the same engaging two of the posts 25, but is allowed to slide longitudinally on these posts against the tension of either one of the two sets of

coiled springs 42, 43 located (as shown in Figs. 5 and 7) respectively on opposite sides of the ears and surrounding the posts 25.

The operation of this controlling device will now be described with particular reference to Figs. 5 and 7. The condition of the parts, as shown in Fig. 5, indicates that the spring 21 has been wound; that is, the driving clutch member is assumed to have engaged the driven member and rotated the same in either direction through the medium of the shaft 11, which rotation has caused either the ratchet wheel 19 or 20 to rotate the gear wheel 24 in a clockwise direction. While doing so, the guide nut 40, which naturally must have participated in this rotation, had also, by engaging the thread on the feed screw 34, first, been forced downwardly thereby against the tension of the springs 42, and later, itself forced the feed screw and driving clutch member upwardly at a time when the tension of the springs 42 was strong enough to overcome the friction between the teeth in the claw clutch. The guide nut 40 and feed screw 34 will now remain in this position, shown in Fig. 5, until the power stored up in the spring 21 has been exhausted. Such a condition of the parts is shown in Fig. 7; that is, the power previously stored up in the spring 21 has been used up in the sending of impulses, and the spring will now be wound the moment the shaft 11 is rotated, because the driving clutch member 13 is in engagement with its mate 12. The clutch member 12 having been so placed by the following movements: the impulse sending mechanism was driven by the rotation of the sleeve 22, which transmitted, through the medium of the carrier hub 36 and the pins 37, rotation to the feed screw 34. The guide nut 40, which during these operations is not rotated, must first have been forced upwardly against the tension of the springs 43, by engagement with the thread on the feed screw, and later itself forced the feed screw and the driving clutch member downwardly at a time when the tension of springs 43 was sufficient to overcome the friction of the feed nut and pin 37 against the carrier hub 36. The guide nut and feed screw will now remain in this position (Fig. 7) and hold the driving clutch member in engagement with its mate until the spring 21 is again sufficiently wound, when the parts will again assume the position shown in Fig. 5 ready for a succeeding operation.

The mechanism for the actual sending of the impulses that go to make up a subscriber's number and which in its operation makes use of the power stored up in the spring 21 will now be described. It consists of the handle 10 having one end fastened to the supporting crank 82 permanently fixed to the shaft 11. The other

end of the handle is provided with an operating knob 83 and a latch pin 44 adapted, when the handle is pressed into the position shown in dotted lines in Fig. 5 against the 5 tension of the spring 45, to enter one of the holes 46 in the top frame plate 47. Close to each one of these holes is marked the number of impulses that are sent out over the line whenever the mechanism is started by 10 the latch pin 44 entering the corresponding hole. A latch plate 48 is mounted on sleeve 22 by means of the hub 87 and the connecting arm 88. This latch plate 48 is provided with a series of apertures 78 of varying 15 lengths, one for each hole in the top plate 47. At each one of these apertures is mounted, in a slot on the plate 48, a starting cam slide 49 having an outside cam surface 50 of approximately the same length as 20 the corresponding aperture, a toothed segment coupler 51 and an inside cam surface 52. The outside cam surface 50 is adapted to be engaged by the latch pin 44 when pressed down in the corresponding aperture 25 of the latch plate 48 and the slide 49 moved thereby toward the center of the machine. Associated with each of these cam slides and engaging the inside cam surface 52 thereof is a spring-actuated operating slide 30 53 which is supported in a slot in the circular plate 54 permanently fixed to an intermediate supporting frame plate 55 by means of the posts 56. These operating slides 53, which are adapted to be pressed inwardly 35 by their corresponding slides 49, have their inside ends so shaped and located that each one will engage a tooth in the starwheel 57 in such a way as to slightly rock the same in the direction of the arrowpoint shown in Fig. 40 8. A pin 58 on said starwheel 57 is engaged by the slotted end of a crank lever 59 pivoted on shaft 60 and mounted on bracket 84, to which shaft is also attached the arm 61. This crank lever and arm will, therefore, 45 participate in the rocking movement of the starwheel. The arm 61 in its rocking movement controls the starting of the impulse sending by having the hook-shaped extension 62 thereon release one of the two fan-like wings of the interrupter 63 which it 50 normally engages. Said wings of the interrupter 63 are adapted to wedge apart the two contact springs 64 and 65 by passing in between the normally closed ends of the 55 springs, shown at 66 in Fig. 5, and thus interrupt the line circuit which is connected to the springs 64 and 65. As soon as the interrupter is thus released from the arm 61, it will start revolving under tension of 60 the spring 21 through the medium of a train of gears 67, 68, 69, 70, 71 and 72. The gear 72 is the driving gear, and, therefore, permanently fixed to the sleeve 22. The interrupter is attached to the pinion 65 67 and the intermediate gears are mounted

in suitable bearings as shown in Figs. 5 and 6. When the spring 21 is thus released to actuate the interrupter 63, the latch pin 44 is locked in an aperture 78 of the latch plate 48 by means of the edge 74 therein engaging the slot 75 on the latch pin. This is done immediately after the plate has started to move in a clockwise direction as the toothed segment coupler 51 which forms part of the cam slide, now registers with the 70 teeth in the revolving gear-wheel 76 permanently fixed to sleeve 22. The interrupter now keeps on revolving until the required number of impulses has been sent out over the line, which number is determined 75 by a varying angular movement of the plate, the duration of which controls the number of impulses to be sent. Said duration is determined by the length of the locking edge 74 in the apertures 78, as said edge 80 will release the latch pin after the plate has moved far enough to allow it to slip away from the slot 75 on the latch pin, the apertures 78 being enlarged at both ends, sufficiently for the entering and releasing of the 85 latch pin. This pin will then consequently allow the cam slide and operating slide to return to the normal position shown in Fig. 4, and also in turn allow the starwheel, 90 crank lever and arm to return to normal 95 position. This will stop the interrupter as the first wing thereof that happened to be in the path of the hook will be immediately engaged thereby. As soon as the toothed segment coupler 51 is released from the 100 gear-wheel 76, the latch plate 48 will be allowed to return to normal position under tension of a spiral spring 77, the inside end of which is attached to the hub of the starwheel and the outside end to the hub 87 of 105 plate 48. This spring also serves to return the starwheel and its associated parts to normal position as the plate and starwheel move in opposite directions when returning to normal, the normal position of the starwheel and the latch plate 48 being determined by the engagement of the arm 61 with interrupter 63 on one hand, and the engagement of projection 85 of plate 48 110 with posts 86 on the other hand. 115

The speed at which the sending of the impulses may take place is controlled and regulated by means of a governing mechanism consisting of the usual weighted springs 78 attached to a worm 79 which meshes with 120 and is rotated by the wormwheel 80 that is in turn attached to the interrupter 63 by means of the shaft 81.

The following is a brief summary of the 125 operation of this invention. The winding of the spring 21 may take place whenever the two members of the claw-clutch are in engagement with each other, either when the handle is turned in a clockwise direction, by means of the pawl 17 engaging the ratchet 130

wheel 19 which is connected to the gear-wheel 24 by means of the posts 25, or when the handle is turned in a counter-clockwise direction, by means of the pawl 18 engaging the ratchet wheel 20 which operates the gear-wheel 24 through the intermediate train of gears 26, 27, 28 and 29. During such winding operations the guide-nut 40 must rotate with the posts 25 and be forced gradually downward on the feed-screw 34 against the tension of the springs 42, and later itself force the feed-screw and driving clutch member 12 upwardly when the tension in the springs 42 is sufficient to do so. During the unwinding of the spring for operations of the sending mechanism, the feed-screw must rotate with the carrier hub 38 and sleeve 22 and force the nut 40 upwardly against the tension of the springs 43 and later the nut itself forces the feed-screw and driving clutch member downwardly when the tension in the springs 43 is sufficient to do so. The shifting of clutch member 12 out of engagement with its mate takes place whenever the spring 21 is fully wound, and the shifting of clutch member 12 in engagement with its mate takes place whenever the spring is run down, but such shifting actions depend principally on a certain amount of power that must first be stored up in either one of the series of springs 42 or 43.

When the handle is depressed for the purpose of sending a series of impulses, the latch pin 44 enters a hole 46 and the corresponding aperture 78 of the latch plate 48 and engages the outside cam surface 50 of the cam slide 49 and moves the same a short distance toward the center of the machine. The operating slide 53, which is forced to participate in this inward movement of the slide 49, is adapted to rock the starwheel 57, which in turn transmits its motion to the crank lever 59 and arm 61. The arm 61 then releases the interrupter 63 which will start to revolve under tension of spring 21 and send impulses over the line by manipulation of the springs 64 and 65. Simultaneously with the release of the interrupter the coupler 51 locks with gear 76 which now is free to revolve, and the latch pin 44 is therefore locked in the aperture 78 by means of the edge 74 therein engaging the slot 75 in the pin. The interrupter 63 and latch plate 48 now keep on revolving until the locking edge 74 releases the latch pin 44 which will take place as soon as it has slipped by the slot 75 on the pin. Immediately after the release of the latch pin 44 all the parts return to normal and the interrupter is stopped. The number of impulses sent by the interrupter depends therefore principally on the duration of the period during which the handle is locked in operated position, and that is determined by the varying

lengths of the edges 74. The mechanism now is ready for the selecting and sending of a second group of impulses representing a digit, and quite a number of such groups may be sent without necessitating the winding of the spring 21 every time the subscriber turns the handle in search of a digit, as a comparatively few movements of the handle in either direction will store up sufficient power in the spring for the sending of several groups of impulses.

It is obvious that many modifications could readily be made in this invention without departing from the spirit thereof. The apparatus herein disclosed should therefore be taken merely as illustrative, and the invention limited merely by the scope of the appended claims.

I claim—

1. In a sender, the combination with a circuit interrupter, of a motor mechanism therefor, means for storing power in said motor mechanism, means for appropriating fractional quantities of power from said motor mechanism, and means for releasing said circuit interrupter to make use of such quantities of power for sending corresponding numbers of impulses.

2. In a sender, the combination with a circuit interrupter, of a motor mechanism therefor, means for storing power in said motor mechanism, a handle for actuating said means, a latch pin on said handle, a latch plate therefor, a plurality of cam slides controlled by said latch pin for coupling said plate to said motor mechanism for the rotation thereof with said mechanism when it is set in motion, means on said slides and plate adapted to coöperate with the latch pin for variously prolonging the coupling period of said plate to said motor mechanism, means controlled by said cam slides for releasing said circuit interrupter and motor mechanism to make use of some of the power stored up in the latter for sending impulses by the former, and for a period equal in each case to the period in which the plate remains coupled to the motor mechanism.

3. In a sender, the combination with a circuit interrupter, of a motor mechanism, means for storing power in said motor mechanism, a handle for actuating said means, a latch pin, a latch plate, a plurality of cam slides controlled by said latch pin for coupling said plate to the motor mechanism for the rotation thereof by said motor mechanism when it is set in motion, cam surfaces of different lengths, one on each slide, projections of different lengths on said plate, each one adapted to lock, by means of the latch pin, with a cam surface of equal length on a slide for prolonging the coupling period of said plate to the motor mechanism, said coupling period being in each case dependent on the length of

- the projection and cam surface so locked by the latch pin, and means controlled by said cam slide for releasing the circuit interrupter and motor mechanism to make use 5 of some of the power stored up in the latter for the sending of impulses by the former, and for a period equal in each case to the period in which the plate remains coupled to the motor mechanism.
- 10 4. In a sender, the combination with a circuit interrupter, of a motor mechanism therefor, means for storing up power in said motor mechanism, a plate, a plurality of cam slides for coupling said plate to said 15 motor mechanism for the rotation thereof, a mechanism coacting with said plate and anyone of said slides for variously prolonging the period in which the plate remains coupled to the motor mechanism when said 20 motor mechanism is set in motion, a sliding member for each of said cam slides, a star-wheel controlled by anyone of said sliding members, a lever mechanism controlled by said starwheel for releasing the interrupter 25 and motor mechanism and allowing the same to operate for a period equal to the period in which the plate remains coupled to the motor mechanism.
5. In a sender, the combination with a circuit interrupter, of a motor mechanism, an operating handle therefor, a mechanism adapted to be actuated by the movement in either direction of said handle for storing power in said motor mechanism, and means 30 for making use of said power by the circuit interrupter for sending impulses.
6. In a sender, the combination with a circuit interrupter, of a motor mechanism, an operating handle therefor, a driving 35 clutch operated by said handle, a mechanism for storing power in said motor mechanism by the movement of the clutch in either direction, and means for making use of such power by the circuit interrupter for sending impulses.
7. In a sender, the combination with a circuit interrupter, of a motor mechanism, an operating handle therefor, a pawl and ratchet mechanism for storing power in said 40 motor mechanism by the movement of the handle in either direction, and means for making use of such power by the circuit interrupter for sending impulses.
8. In a sender, the combination with a circuit interrupter, of a motor mechanism, an operating handle therefor, a mechanism controlled by the handle for storing power in said motor mechanism and comprising a pawl and ratchet mechanism adapted to be 45 come active when the handle is turned in one direction, a similar mechanism adapted to become active when the handle is turned in the opposite direction, and a means for making use of said power by the circuit interrupter for sending impulses.
9. In a sender, the combination with a circuit interrupter, of a motor mechanism, an operating handle therefor, means for storing power in said motor mechanism, a driving clutch for said means controlled by 50 said handle, means for controlling the engagement and disengagement of said clutch with said power storing means, and means for making use of said power by the circuit interrupter for sending impulses. 75
10. In a sender, the combination with a circuit interrupter, of a motor mechanism, an operating handle therefor, means for storing power in said motor mechanism, a driving clutch for said means controlled by 55 said handle, a feed screw for controlling said clutch, means for controlling the feed screw to automatically engage or disengage the clutch with said power storing means, and means for making use of such power by the circuit interrupter for sending impulses. 80
11. In a sender, the combination with a circuit interrupter, of a motor mechanism, an operating handle therefor, means for storing power in said motor mechanism, a driving clutch for said means controlled by 60 said handle, a feed screw for controlling said clutch, a guide nut for controlling the feed screw to automatically engage and disengage the clutch with said power storing 90 means, means for automatically operating said guide nut to effect the engagement of the clutch with the power storing means when said means is in a run-down condition and to effect the disengagement of the clutch 95 with the power storing means when said means has stored full power, and a means for making use of such power by the circuit interrupter for sending impulses. 100
12. In a sender, the combination with a circuit interrupter, of a motor mechanism, an operating handle therefor, means for storing power in said motor mechanism, a driving clutch for said means controlled by 105 said handle, a feed screw for controlling said clutch, a guide nut for guiding said feed screw in its movement, two sets of springs for alternately controlling said feed screw through the medium of the guide nut, a mechanism associated with and controlled by the power storing means for 110 revolving, when the clutch is engaging the power storing means, the guide nut against the tension of one set of springs and causing it by means of the feed screw to disengage the clutch from active engagement with the power storing means at a time when a sufficient tension has been stored up in said sets of springs to effect such a disengagement, and a mechanism associated 115 with and controlled by the power storing means for revolving, when the clutch is disengaged from control over the power storing means, the feed screw to cause it through the coöperation of the guide nut, which now 120
- 130

is raised against the tension of the other sets of springs, to engage the clutch with the power storing means at a time when a sufficient tension has been stored up in said 5 set of springs to effect such a disengagement, and means for making use of such power by the circuit interrupter for sending impulses.

13. In a sender, the combination with a 10 circuit interrupter of a motor mechanism, an operating handle therefor, a mechanism adapted to be operated when the handle is turned in one direction to store up energy in said motor mechanism, and a mechanism 15 adapted to be operated when the handle is turned in an opposite direction to store up energy in said motor mechanism, and means for making use of such power by the circuit interrupter for sending impulses.

20. 14. In a sender, the combination with a

circuit interrupter of a motor mechanism, an operating handle therefor, a pawl and ratchet-like means adapted to operate said motor mechanism when the handle is turned in one direction, a train of gears, and a pawl 25 and ratchet-like means connected with said motor mechanism by means of said train of gears and adapted to operate when the handle is turned in the opposite direction, and means for making use of such power 30 by the circuit interrupter for sending impulses.

In witness whereof, I hereunto subscribe my name this 24 day of September A. D., 1914.

JOHN A. KROPP.
